UNITED STATES PATENT OFFICE.

PETER M. KLING, OF ST. LOUIS, MISSOURI.

DESIGN FOR A HAND-RAIL FOR CAR-SEATS.

SPECIFICATION forming part of Design No. 31,814, dated August 1, 1899.

Application filed June 19, 1899. Serial No. 721,145. Term of patent 14 years.

To all whom it may concern:

Be it known that I, PETER M. KLING, a citizen of the United States, and a resident of the city of St. Louis, in the State of Missouri, have 5 invented and produced a new and original Design for a Hand-Rail for Car-Seats, of which the following is a specification, reference being had to the accompanying drawing, forming part thereof.

① The drawing is a perspective view showing my new design.

As shown in the drawing, the leading or material feature of my design consists in a bar

2, having a pendent post 5 at its middle portion and rounded brackets 4 at its ends provided with inwardly-extending projections 3.

Having thus described my invention, the following is what I claim as new therein and desire to secure by Letters Patent:

The design for a hand-rail for car-seats; substantially as shown and described.

PETER M. KLING.
